UNITED STATES PATENT OFFICE.

ROBERT SHIELDS, OF SOUTH BOSTON, MASSACHUSETTS, ASSIGNOR TO
FRANK RIDLON COMPANY, OF BOSTON, MASSACHUSETTS, A CORPORA-
TION OF MASSACHUSETTS.

TROLLEY-CATCHER.

No. 858,355.

Specification of Letters Patent.

Patented June 25, 1907.

Application filed March 14, 1906. Serial No. 305,986.

To all whom it may concern:

Be it known that I, ROBERT SHIELDS, a citizen of the United States of America, residing at South Boston, in the county of 5 Suffolk and State of Massachusetts, have invented a new and useful Trolley-Catcher, of which the following is a specification:

My invention relates to improvements in controlling devices for trolley-pole cords, in 10 which a spool or reel is mounted in a suitable case with means to lock such reel to said case and release it therefrom under certain varying conditions and with other means for so connecting a mainspring with said reel and its 15 supporting stud that said mainspring is affected only when the reel is rotated in one direction, that is, in the direction for paying out the rope or cord wound thereon, certain subsidiary and auxiliary parts and members 20 being provided, all as hereinafter set forth.

The object of my invention is to provide a trolley catcher which, while performing all of the offices and meeting all of the requirements of which such a device is capable, is 25 simple, convenient, and unusually strong and durable.

In order to successfully withstand the repeated shocks incident to the locking of the rapidly revolving reel every time the cord is 30 drawn swiftly upward under the influence of the trolley-pole spring when the trolley-wheel leaves the over-head wire, it is necessary to furnish the device with exceedingly substantial locking mechanism, and such 35 provision constitutes an important feature of this invention. In the present construction the line of resistance is straight instead of curved and the locking mechanism consequently more powerful. Provision is also 40 made for whatever back-lash of the reel, upon the rebound of the trolley-pole, occurs without unlocking the parts.

Other objects will present themselves in the following description.

45 I attain these objects by the means illustrated in the accompanying drawings, in which—

Figure 1 is a front view of the trolley catcher without the front section of the case, 50 wherein portions of the reel and of the face plate are broken away and one of the locking pawls on said reel is shown in engagement

with the dog or stop in the back section of the case; Fig. 2, a rear view of the reel, the pawls being presented in their non-active positions in full lines and in their active positions by dotted lines, the relative position of the stop is also here shown by dotted lines; Fig. 3, an inside view of the front section of the case; Fig. 4, a front, end view of the anchorage sleeve for the mainspring; Fig. 5, a front end view of the axial stud; Fig. 6, a rear, end view of the aforesaid sleeve; Fig. 7, a side view of a modified form of axial stud and associated members; Fig. 8, a central 60 vertical section through the device as a whole taken from front to back and looking toward the left of Fig. 1; Fig. 9, a fragment of the case with a part of the projection which forms the passage for the trolley cord, 70 showing a length of chain caught in the notch in said projection, and, Fig. 10, still another modified form of axial stud and associated members.

Similar figures refer to similar parts 75 throughout the several views.

It is to be understood that, as is usual in devices of this kind, the mainspring acts upon the reel to wind up the slack in the trolley cord and yields to allow said cord to 80 unwind—that is to say, when the cord is carried upward the mainspring is itself wound up. As before intimated provision is made to release the mainspring after it has expended its force, so as to avoid straining and 85 possibly breaking the same. It is to be understood, furthermore, that the case is to be fastened in any suitable manner and by any suitable means to the dasher of a car, but since such fastening means forms no part of 90 this application the same is omitted except for a flange on the back of the case which may be utilized for such a purpose.

I will now proceed to describe in detail a preferred construction of my device. The 95 case herein provided consists of a back section 1 and a front section 2, the latter having a flange 3 at its inner rim to lap over the inner rim on the former. For the passage of a trolley cord the case is provided with a projection 4 having a passage therethrough. In one side of the projection 4 is a notch 5 adapted to receive and hold the end of a short length of chain, which may be used as a 100

connecting medium between the reel and cord, when said reel is under tension, for reasons which will appear hereinafter. The bottom of the case is cut out to form a hand-hole 6, which permits of the escape of any water that may collect in the case and allows the operator to introduce his fingers into the case for the purpose of manipulating the reel and fastening the cord thereto. In order to assist in bringing the section 2 into proper relationship with the section 1 and to prevent these parts from turning upon each other I make use of a lug 7 on the rear section adapted to enter an indentation 8 in the flange 3 on the front section. A flange 9 on the back side of section 1 may be employed for attaching the device to the car dasher, as already noted. Within the flange 9 is an internally screw-threaded hub 10 for an axial stud 11 which is screwed tightly into place in this hub with an enlarged part or shoulder bearing against the inside face of the back of the section 1. When the front section 2, which partakes of the nature of a cover, is in position the front, screw-threaded terminal of the stud 11 extends through a hole 12 in said section to receive a nut 13 which assists in securing the two sections together.

Within the case is a reel 14 having a hub 15 loosely mounted on the enlarged portion of the stud 11. The reel 14 has a chamber 16 therein. An anchorage sleeve 17, for a mainspring 18, is loosely mounted on the diminished portion of the stud forward of that portion of said stud which directly supports said reel, and a plate 19, which serves as a rear support or backing for the mainspring 18, is mounted on the stud between the front end of the hub 15 and the rear end 40 of said sleeve. A face plate 20 is screwed onto the front, threaded terminal of the stud 11 to assist in retaining the sleeve 17 in place and to close the front of the chamber 16, the mainspring being confined laterally between this plate and the plate 19. The members 19, 17 and 20 together with the back side of the section 1 hold the reel 14 against movement longitudinally of the stud 11. The inner end of the mainspring 18, which has 50 first been bent into suitable shape, is attached to the sleeve 17 by being inserted in a longitudinal slot 21 provided in said sleeve for that purpose, as shown at 22, while the outer end of said mainspring is fastened to a pin 23 seated in a projection 24 in the chamber 16. On the rear end of the sleeve 17 are ratchet-teeth 25 arranged to engage a pin 26 so situated in the stud 11 that its front end projects into the path of said ratchet-teeth, a spring 60 27 behind said pin constantly tending to force it outward. As will be readily seen the pin 26 prevents the sleeve 17 from being rotated in one direction, but offers little resistance when said sleeve is rotated in the opposite direction.

When the reel 14 is revolved in the direction of the arrow in Fig. 1, the mainspring 18 will be wound up, because the sleeve 17, to which the inner end of said mainspring is attached, is prevented from rotating by the pin 26 and the engaging ratchet-tooth 25; but when said reel revolves or is revolved in the opposite direction, after the mainspring runs down it will not be distorted or broken by the continued rotation of the reel, owing to the fact that the ratchet-teeth 25 now slip by said pin, the spring 27 yielding for this purpose. This arrangement not only takes care of any momentum that might be imparted to the reel by the unwinding of the mainspring, but helps to overcome the same. Moreover, the ratchet mechanism enables the surplus cord to be wound on the reel by rotating the reel in the opposite direction to that indicated by the aforesaid arrow. 85

A perforated lug 28, Fig. 8, is provided at some suitable point on the reel, to which and from which either a short length of chain 29 or a cord 30 may be easily and quickly attached and detached. When the chain 29 is employed the cord 30 is fastened thereto. The object of using a chain is to afford convenient means for holding the reel against rotation, when the mainspring is wound up, at such times as it is desired to remove the device from one car to another and consequently to change trolley cords; this is accomplished by drawing the chain out through the projection 4 and catching its outer end in the notch 5, as shown in Fig. 9. While the chain is in this position the change in cords can be made, after which said chain is released and permitted to be wound onto the reel with part of the attached cord, the mainspring performing this work. 100 105

The cord 30, whether attached directly to the reel or connected with the chain 29, is originally wound on the reel 14 in either of two ways: first, by taking turns of said cord about said reel while the cover section 2 is off, the mainspring remaining inactive and being undisturbed; and, second, by reaching through the hand-hole 6 and rotating the reel in the contrary direction to that indicated by the arrow in Fig. 1, the ratchet-teeth 25 meanwhile clicking past the pin 26. Now any upward pull on the cord will cause the mainspring to be wound up, more or less, accordingly, and when the cord is slackened said mainspring will in turn cause the slack to be again wound on the reel. Thus is the cord kept taut under all ordinary circumstances. 110 115 120

The reel 14 is equipped on the back with a plurality of abutments 31 and pawls 32, there being three of each in the present instance, although this number may vary. The abutments 31 are fixed immovably to the reel, but the pawls 32 are pivoted thereto, the inner end of each of the latter being 125 130

mounted on a pivot 33 extending rearward from said reel. Each pawl 32 is so formed and located that its movement in one direction is limited by the adjacent end of one abutment 31 and in the other direction by the adjacent end of another abutment; in other words, each pawl can oscillate between and contact with two adjacent abutments. The pawls are normally drawn inward and retained with their outer ends or heads in contact with what may be termed the feet of the abutments by means of light springs 34. Each spring 34 has one end fastened to the reel and the other end to a pawl. Within the section 1 behind the reel 14, a little remote from the path of travel of the abutments, is a dog or stop 35, and when the pawls are in the position just noted they also clear said stop as the reel revolves, provided such revolution be regular and even and insufficient to overcome by centrifugal force the power of the spring 34, but under a sudden acceleration of speed imparted to the reel in the direction of the arrow, as when the trolley-wheel slips from the wire and the cord attached to the trolley-pole is suddenly jerked upward, the power of said springs is overcome and the pawls swing outward until their heads contact with the heads instead of the feet of the abutments, each pawl now bearing against the abutment behind, in the line of rotation, that against which it had previously rested. The stop 35 is now in the path of the pawls. (See the parts 32 and 35 in full lines in Fig. 1 and in dotted lines in Fig. 2.) Immediately one of the pawls 32 encounters the dog 35 and stops further movement of the reel, thus checking the cord and trolley-pole. The force of the blow when the shock between the contacting members 32 and 35 occurs is distributed throughout these members and the abutment between which and the stop the acting pawl is grasped, and the line of resistance is practically straight as will be seen upon referring to Fig. 2, hence the strength and durability of this mechanism.

In case the trolley-pole rebounds, when first checked in its upward flight as before explained, and the reel is released for an instant by the consequent slackening of the cord, the mainspring immediately acts to rotate said reel thereby causing the active pawl 32 and its engaging abutment 31 to separate, but since the amount of such rotation is necessarily slight, because the force of the rebound is quickly expended, and owing to the peculiar arrangement of the locking members such pawl does not clear the stop 35 before said cord is again drawn up by the trolley-pole, which action rotates the reel in the opposite direction or against the mainspring until the three locking members are once more in contact, when further motion ceases. From the foregoing it will be seen that the liability of prematurely unlocking the reel

and releasing the trolley-pole is removed. When the reel is released, upon the drawing down of the cord to replace the trolley-wheel on the wire by the operator, the mainspring unwinds and rotates the reel in the proper direction to cause the locking members to become disengaged, the device being now unlocked and ready for a repetition of the action hereinbefore described. It will be understood that the springs 34 have, since the time that the reel was first locked, returned all of the pawls 32 to normal position by drawing them inward so that they clear the stop 35.

Referring to Fig. 7 it will be noticed that a fixed pin 26^a is employed, in place of the spring-actuated pin 26, and that the sleeve 17 here has endwise movement, a spring 27^a being introduced between the face plate 20 and the adjacent end of the sleeve to force the latter into engagement with said pin 26^a. The pin 26^a projects forward from a flange 36 on the enlarged portion of the stud 11. The operation of this mechanism is the same as that of the corresponding mechanism best shown in Fig. 8 and already fully described, excepting that the sleeve is forced forward against the resiliency of the spring 27^a every time one of the ratchet teeth 25 rides over the pin 26^a, while in the other instance the pin is forced backward out of the way of the ratchet-teeth.

In the Fig. 10 construction a stud 11^a made in two parts screwed together is used, with a washer 36^a immovably secured between the aforesaid parts of the stud. The washer 36^a takes the place of the flange 36 in the Fig. 7 construction, and like said flange is provided with a pin 26^a. Except in the particulars mentioned the two modified constructions are practically the same.

Under some circumstances in some climates I find it desirable to provide for permanent lubrication of the bearings of the spool and for this purpose I prefer to fill the opening between the plate 19 and the back of the spool with tow or other like material and saturate the same thoroughly with a suitable lubricant. I also provide suitable oil conduits leading from said chamber to the bearing parts, one such conduit appearing at 37 in Fig. 8. The oil will flow from the chamber through the conduits to the bearings and keep the same constantly oiled until the surplus oil in the chamber has become exhausted. With this construction the device may be used very many months without replenishing the oil.

Having therefore described my invention, what I claim and desire to secure by Letters Patent, is—

1. In a trolley catcher, the combination of a suitable supporting case having therein a fixed inwardly projecting stop, a rotating reel mounted in said case, a spring to rotate

the reel in one direction, a pawl pivotally mounted on the face of the reel and arranged when outwardly disposed to engage said fixed stop on the case, an abutment on said reel located in the path of the head of the pawl to limit the extent of the outward movement of the pawl and take the thrust or blow caused by the impact of the pawl against the fixed stop on the case, and means to normally hold the pawl out of the path of the fixed stop.

2. In a trolley catcher, the combination of a suitable case, a fixed stop projecting inwardly from the case, a rotating reel mounted in the case, a plurality of pawls pivotally mounted on the face of the reel adjacent the central portion of the reel, abutments mounted on the reel in the path of and at the limits of movement of the pawls where-
15 by their movement is limited in both direc-
tions and the abutments receive the blows or
impacts caused by the engagement of the
pawls with the fixed stop on the case, and
means to normally hold the pawls out of the
20 path of the fixed stop.

3. The combination, in a trolley catcher, of a case having an internal fixed stop, an axial stud mounted in the case, a reel mounted to revolve on said stud, inwardly spring-actuated
30 pawls mounted on said reel, and abutments also mounted on the reel against which abutments the pawls bear when outwardly dis-
posed, said stop being located out of the path
of said pawls when the reel revolves except-
35 ing when said pawls are thrown outward by
centrifugal force at which time one of the
pawls is caught between said stop and one of
said abutments, substantially as shown.

4. In a trolley catcher, the combination of a suitable case, a reel mounted to revolve therein, a fixed stop on the case, a pawl mounted on the face of the reel said pawl being normally held out of the path of said fixed stop when the reel revolves, and adapted to
40 be moved into the path of the fixed stop by
centrifugal force when the reel revolves with
sufficient rapidity to overcome the force holding the pawl normally out of such path, an
abutment mounted on said reel adjacent the
45 head of the pawl and in recurring right line
relation with the fixed stop whereby the
50 force of the blow caused by the sudden stop-
page of the revolution of the reel by the pawl

engaging the fixed stop will be borne by the abutment, substantially as shown.

55

5. The combination, in a trolley catcher, of a case, an axial stud therein, a revoluble reel mounted on such stud, a revoluble anchorage sleeve on the stud, ratchet-teeth on such sleeve, a spring-pressed pin projecting from said stud into engagement with said ratchet-teeth, and a mainspring having one end connected with said wheel and the other end attached to said sleeve.

6. The combination, in a trolley catcher, of a case, an axial stud therein, a hollow revoluble reel mounted on such stud, a revoluble anchorage sleeve also mounted on the stud and held against endwise movement thereon, ratchet-teeth on the inner end of such sleeve, a spring-pressed pin projecting from said stud into engagement with said ratchet-teeth to limit the revolution of said sleeve in one direction, a mainspring in the reel chamber having one end connected with said reel and the other end attached to the sleeve, and plates on the stud between which said main-
70 spring is located.

7. The combination, in a trolley catcher, of a case, an axial stud therein, a revoluble reel mounted on such stud, a revoluble sleeve also mounted on the stud, ratchet-teeth on such sleeve, means to prevent end-
80 wise movement of the sleeve, a spring-pressed pin in said stud, extending into the path of said ratchet-teeth to limit the revolution of said sleeve in one direction, and a main-
85 spring having one end connected with the reel and the other end attached to the sleeve.

8. A trolley catcher, comprising an outer case, a centrally recessed reel mounted to revolve in the case, a plate separating said recess into two non-communicating compartments, a spring in one of said compartments, the other compartment forming an oil reservoir, and a conduit leading from the oil reservoir to the reel bearing, substantially as
90 shown.

In testimony whereof I have signed my name to this specification in the presence of two subscribing witnesses.

ROBERT SHIELDS.
